United States Patent Office

Des. 218,160

Patented July 28, 1970

218,160

VEHICLE SEAT

Edgar J. Smith, Rte. 1, Mitchell, S. Dak. 57301

Filed Dec. 13, 1968, Ser. No. 14,961

Term of patent 14 years

Int. Cl. D6—01

U.S. Cl. D15—8

FIG 1

FIG 2

FIG 3

FIG 4

FIG 5

FIG 6

FIG. 1 is a perspective view of a vehicle seat embodying my new design;

FIG. 2 is a right side elevation view of the vehicle seat; the left side view being a mirror image of the same;

FIG. 3 is a front elevation view of the same;

FIG. 4 is a rear elevation view of the same;

FIG. 5 is a top view of the same; and

FIG. 6 is a bottom view of the same.

I claim:

The ornamental design for a vehicle seat, as shown and described.
